FLOOR AND CARPET TREATING MACHINE

Carroll M. Gantz, North Canton, Ohio, and Robert H. Hose, Mountainside, N.J., assignors to The Hoover Company, North Canton, Ohio, a corporation of Ohio

Filed Nov. 15, 1966, Ser. No. 4,674

Term of patent 14 years

(Cl. D37—3)

Fig. 1

Fig. 2

Fig. 3

The dominant features of our design reside in the portions shown in full lines.

We claim:

The ornamental design for a floor and carpet treating machine, substantially as shown and described.
